UNITED STATES PATENT OFFICE.

AUGUSTUS A. GULLETT, OF AMITE CITY, LOUISIANA.

FRICITION REVERSING-GEARING FOR PRESSES.

SPECIFICATION forming part of Letters Patent No. 244,050, dated July 12, 1881.

Application filed May 12, 1881. (Model.)

To all whom it may concern:

Be it known that I, AUGUSTUS A. GULLETT, a citizen of the United States, residing at Amite City, parish of Tangipahoa, and State of Louisiana, have invented certain new and useful Improvements in Friction Reversing-Gearing for Presses, of which the following is a specification.

This invention relates specially to cotton, 10 hay, and moss presses, but may be used for other machines; and the nature of the same consists in a driving pulley or gear shaft having one of its ends applied laterally movable in a fixed bearing-box of a press-frame and 15 its other end applied loosely in an oscillating gear-frame carrying two gear-wheels and two friction-pulleys, said gear-frame and driving-pulley shaft being arranged to alternately bring 20 its friction-pulleys in gear with another friction-pulley on a shaft, which applies the power to a shaft which works the gearing of a screw or other press, the action being such that the 25 screw of the press will be run up or down or back and forward to do the work of pressing cotton or other substances, and then to run the screw back for another operation with increased speed, and all while the driving-pulley shaft is revolving in the same direction.

In the accompanying drawings, Figure 1 is 30 a perspective view of my invention and a portion of a press to which it is applied, showing the driving-shaft in an oblique position. Fig. 2 is a side elevation of the same; and Fig. 3 is 35 a detail sectional view of a portion of the driving-shaft and its bearing, the shaft being shown parallel with the frame of the machine or press.

A represents a portion of a cotton or other press; B, the screw; C, a large bevel-wheel on the screw; D, a smaller bevel-wheel on the 40 power-applying shaft, and gearing into wheel C. On shaft E a large friction-pulley, F, is applied.

G is the driving-pulley shaft, carrying a pulley, H, at one end.

I is a pivoted oscillating frame, hung on a pivot, b, in a fixed hanger, a, of the press-frame A. This swinging frame is provided with two sets of bearing-boxes, c c', and in the boxes c of said frame I, and the box of bearing c' of the 50 frame A, the pulley-driving shaft G is fitted to

revolve, as well as to have freedom to vibrate in the box of bearing c' as the frame I is oscillated.

In the space between the side bars of the swinging frame I, and on the shaft G, are applied a friction-pulley, J, and a toothed gear-wheel, K, said friction-pulley and gear-wheel being keyed fast on the shaft G and revolving together and with said shaft.

Immediately above the pulley J and gear-wheel K a pulley, L, and gear-wheel M are applied on a short spindle fitted in the other set of boxes, c'. The pulley L is of greater diameter than the pulley J, while the gear-wheel M is of less diameter than the gear-wheel K. 65 The two pulleys J and L can respectively be made to bear with a frictional and driving contact upon the large friction-pulley F. The two gear-wheels K and M gear with one another and cause the pulleys J and L to revolve in 70 opposite directions, as indicated by the arrows 1 and 2 in the drawings.

A lever, N, is rigidly fastened to a bracket of the frame I, and by means of this lever the frame I can be oscillated so as to bring either 75 of the pulleys J and L into frictional contact with the pulley F, and thereby cause the pulley F to move or revolve in either the direction of the arrow 3 or the arrow 4, accordingly as it is desired to have the shaft E revolved. 80

If the frame I is adjusted to throw the pulley J in contact with the pulley F, the shaft E, in revolving, will cause the bevel-wheels C D to work the power-screw B, which carries the platform of the press, with an upward or pressing 85 effect; but if the said frame is adjusted to throw the pulley L in contact with the pulley F while the pulley J is moved out of contact with said pulley F, the direction of the movement of the said shaft E and the pulley F will be reversed 90 and the bevel-wheels C D will be caused to run down or back the screw. The diametrical proportions of the gear-wheels K and M and pulleys J and L will be determined in accordance

with the relative speeds at which it is desired 95 to have the screw move up and down, and as the design is to have the screw move upward with a slow speed while pressing and downward with a fast speed while not pressing, the pulley J will be made smaller in diameter than 100

the pulley L, in order to get the desired slow speed upward, and the pulley L larger than the pulley J to insure the faster down speed.

The operation of the mechanism described is rendered exceedingly simple as compared with other reversing mechanism heretofore employed by having the pulley-shaft capable of vibrating in the box of bearing c^2 , and then having its opposite end hung in an oscillating frame, I, carrying the gear-wheels and friction-pulleys, such frame being provided with a rigid lever or arm, and also arranged upon the frame of the press in compact relation to the pulley of the power-applying shaft. The lever or arm 15 N is so arranged above the fulcrum or pivot b of the frame I that the friction-pulleys J and L may be applied with great force, and, if desired, a weight may be hung upon this lever or arm for the purpose of maintaining the frictional contact between the pulleys.

My invention is applicable for reversing the movement of other machines than screw-presses, and therefore is not confined to such presses.

Prior to my invention reversing-gearing of 25 various descriptions has been contrived; but

in none of these has a pulley-driving shaft, G, which is fitted at one end in a fixed box, so as to allow its other end to swing back and forth, been employed; nor has such shaft been connected by its swinging end with a swinging frame carrying reversing-gears in the manner shown by me.

What I claim as my invention, and desire to secure by Letters Patent, is—

1. The combination of the vibrating driving-pulley shaft G, the oscillating frame I, the friction-pulleys and gear-wheels on said frame, and a friction-pulley on a power-applying shaft of a press or other machine, substantially as and for the purpose described. 35

2. The swinging frame I, provided with a lever or handle and with friction-pulleys and gear-wheels, and hung in a bracket of the press or other frame, in combination with the vibrating pulley-driving shaft and with the pulley power-applying shaft, substantially as described. 40 45

AUGUSTUS A. GULLETT.
